(57) **CLAIM**

The ornamental design for a backpack as shown and described.

DESCRIPTION

FIG. 1 is a front, right view of a backpack showing my new design;

FIG. 2 is a rear, left view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front, right exploded view showing the interior package outside of the backpack.

The dash-dash broken lines in the drawings depict portions of the backpack that form no part of the claimed design.

1 Claim, 9 Drawing Sheets
